(57) **CLAIM**

The ornamental design for earphones with charging case, as shown and described.

DESCRIPTION

FIG. 1 is a top perspective view of a charging case of the earphones with charging case showing my new design, the case is shown separately for ease of illustration;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view thereof, in an open position;

FIG. 10 is a top perspective view of the earphones with charging case thereof, in an open position;

FIG. 11 is a top perspective view of an earphone of the earphones with charging case shown separately for ease of illustration;

FIG. 12 is a bottom perspective view thereof;

FIG. 13 is a front view thereof;

FIG. 14 is a rear view thereof;

FIG. 15 is a left side view thereof;

FIG. 16 is a right side view thereof;

FIG. 17 is a top view thereof;

FIG. 18 is a bottom view thereof;

FIG. 19 is a top perspective view of an earphone, of the earphones with charging case shown separately for ease of illustration;

FIG. 20 is a bottom perspective view thereof;

FIG. 21 is a front view thereof;

FIG. 22 is a rear view thereof;

FIG. 23 is a left side view thereof;

FIG. 24 is a right side view thereof;

FIG. 25 is a top view thereof;

FIG. 26 is a bottom view thereof; and,

FIG. 27 is an enlarged detail view of area 27 in FIG. 12. The broken lines in the drawings illustrate the portions of the earphones with charging case, which form no part of the claimed design.

The dot dash broken lines encircling a portion of the earphones with charging case in FIG. 12 and illustrated in the enlarged view of FIG. 27 form no part of the claimed design.
